CLAIM

The ornamental design for a romper, as shown and described.

DESCRIPTION

FIG. 1 is a front, top, right side view of a romper in a closed configuration showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a front, top, right side view thereof in an environment of use with the romper being worn by a child.

FIG. 9 is a front, top, right side view of the romper in an open configuration showing the new design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a front, top, right side view thereof in an environment of use with the romper being worn by a child; and,

FIG. 17 is a rear, bottom, perspective view thereof showing a rear portion of the romper being lifted to reveal an interior portion of the romper.

The broken lines in the drawings depict portions of the romper which form no part of the claim. The additional broken lines showing a person depict environment which forms no part of the claim.

1 Claim, 11 Drawing Sheets
